UNITED STATES PATENT OFFICE.

HARVEY L. FISHER, OF DES MOINES, IOWA.

PRINTING-PRESS.

SPECIFICATION forming part of Letters Patent No. 545,472, dated September 3, 1895.

Application filed January 19, 1895. Serial No. 535,501. (No model.)

To all whom it may concern:

Be it known that I, HARVEY L. FISHER, a citizen of the United States of America, residing at Des Moines, in the county of Polk and State of Iowa, have invented a new and useful Printing-Press, of which the following is a specification.

The object of this invention is to provide a simple, cheap, durable, and easily-operated printing-press of the class known as "cylinder presses," adapted to print direct from the form, capable of printing a comparatively large number of copies in a given time, and be operated either by hand or power.

My object is further to provide mechanism for operating the impression member or cylinder, so that its speed of rotation will be greatest at the center of the type-bed and will gradually decrease toward each end, so that said impression member may be moved rapidly and not injure the machine by abrupt starting and stopping at the ends, to provide simple and easily-operated means for throwing the operating mechanism in and out of gear, and to provide simple, strong, and durable means for automatically elevating the impression member above the form on its backward movement and for adjusting the pressure of the impression member on the form.

My invention consists in certain details in the mechanism for imparting motion to the lazy-tongs levers, the mechanism for throwing the machine in or out of gear, the mechanism for automatically elevating the impression member on its backward or return movement and for adjusting the pressure of the impression member on the form, and in certain other features hereinafter set forth, pointed out in my claims, and illustrated in the accompanying drawings, in which—

Figure 1 is a perspective view of the complete press. Fig. 2 is a longitudinal sectional view of the same. Fig. 3 shows the end of the sliding bar for throwing the mechanism in and out of gear. Fig. 4 shows the device for elevating the cylinder-track. Figs. 5 and 6 are respectively top and side views of the mechanism for operating the lazy-tongs levers and for throwing them in and out of gear with the driving-shaft. Fig. 7 is a perspective view of the cam for operating the track-

elevating mechanism, &c. Fig. 8 is a detail view of the large gear-wheel, showing the spring-actuated pawls in position therein. Fig. 9 is a detail sectional view of the mechanism for throwing the machine in and out of gear, and Figs. 10 and 11 are perspective views of the said pawls.

Referring to the accompanying drawings, the reference-letter A is used to indicate the supporting-legs of the press, A² the type-bed, A³ the parallel tracks at the sides of the bed and a slight distance above the bed, and A⁴ the feeding-platform at one end of the frame above the tracks. These parts are preferably made from cast metal and of the usual shape and size.

B indicates a power-shaft mounted in suitable bearings in the machine-frame beneath the feeding-platform and provided with a belt-wheel or hand-wheel B² on one end, by which it may be driven by power or by hand and with a bevel gear-wheel B³ on its inner end.

C indicates a bevel gear-wheel of much larger diameter than the wheel B² and in mesh therewith and supported in the frame in a horizontal position. C² is a stub-axle passed through the machine-frame and secured thereto by a nut C³. The top central portion of the said wheel is raised at C⁵ and has a vertical bore at D, into which is dropped a coil-spring D² and a pawl D³, having a lug D⁴ at its outer side and an inclined top surface at D⁵. A horizontal slot F is also formed in said raised portion C⁵, leading radially outward from said bore, and F² is a pawl adapted to move horizontally in said slot, with its top projecting a slight distance above the part C⁵ and a shoulder F³ on its inner end adapted to engage the lug D⁴ on the pawl D³. Its inner face at F⁴ is beveled, and a spring F⁵ engages its outer end and normally forces it inwardly to engage the pawl D³. It will be obvious that when the pawl D³ is depressed the shoulder F³ will engage the lug D⁴ and hold the pawl D³ downwardly and when the pawl F² is forced outwardly said pawl D³ will be automatically elevated above the surface C⁵.

H indicates a bar slidably mounted on the machine-frame and provided with a cam on its end arranged to project downwardly and rest upon the surface C⁵ and be capable of

passing between the pawls D³ and F², or to have its inclined surface H² engage the inclined surface D⁵ of the pawl D³ to force said pawl downwardly as the gear-wheel is turned, 5 or else have its cam-surface H³ engage the top of the pawl F² and force it outwardly, thus releasing the pawl D³ and permitting it to move upwardly. This sliding bar H is normally held inwardly to pass between the two 10 pawls and keep pawl D³ in its retracted position by means of the coil-spring H⁴, but may be moved outwardly to engage the pawl F² and permit the pawl D³ to raise and thus throw the mechanism in gear by a downward 15 pressure upon the treadle J, which is connected with the said bar by means of a rod J² and bell-crank lever J³.

K indicates a segment loosely mounted on the upper end of the stub-axle C² and held 20 thereon by the screw K². Formed integral with its central portion K³ and projecting in an opposite direction from the segment K is an arm K⁴, and on the under side of the central part K³, beneath said arm, is a concentric 25 segmental projection K⁵, adapted to be engaged by the pawl D³ when it is in an elevated position. It will now be obvious that when the sliding bar H is held inwardly by its operating spring, upon each revolution of the gear- 30 wheel the inclined surface H² on its end will pass over the pawl D³, and thus allow the gear-wheel to rotate independently of the segment, and when said sliding bar is held outwardly the cam-surface H³ will engage the 35 pawl F² and force it outwardly and permit the pawl D³ to raise, and, when turned to engage the downward projection K⁵, and thus rotate said segment K and arm K⁴. The 40 downwardly-projecting segment K⁵ is so positioned relative to the arm K⁴ that when the device is thrown out of gear the arm K⁴ will stop just before it reaches the limit of its rearward stroke, so that as it is again started the said arm will first be drawn rearwardly a 45 slight distance and then backwardly. By this arrangement the impression member will be started by first moving a slight distance rearwardly and giving the paper-clutching devices thereon a chance to engage a paper 50 from the feeding-platform.

M indicates a series of lazy-tongs levers, one end of which is pivotally connected with a yoke M², that has the axle M³ of the impression member or cylinder M⁴ mounted therein, and 55 the two meeting levers at the opposite end are pivoted to a suitable stationary part of the frame and are provided with segmental gear-wheels M⁵ in mesh with each other. To firmly hold said cylinder in a plane at right 60 angles to the tracks, I have provided the cables M⁶, wound upon the ends of the cylinder two complete turns, secured thereto at the central portion of the cables, and stretched tight and secured at the ends of the tracks in 65 an ordinary manner.

N indicates a link pivotally connected with the end of the crank and with one side of the

lazy-tongs levers in such a manner that the levers will be at one or the other of the limits of their movement when the said arm and link are in alignment. By this arrangement the impression-cylinder will be moved more rapidly when at the center of its movement and will slow up gradually toward each end. On the top surface of each of the tracks A³ is 70 a flat metal bar P, secured thereto only at its ends and capable of being slightly raised at the central portion. P² indicates a block mounted in the frame beneath each of said bars and adapted to move vertically to force 75 said bar upwardly.

P³ indicates two rock-shafts mounted in suitable bearings in the machine-frame beneath the type-bed and each provided with downwardly-projecting arms P⁴, connected 85 by rods P⁵, so that they will move in unison, and R indicates disks on their ends having notches R² therein and the blocks R³ resting in said notches and engaging the lower ends of the blocks P², so that a movement of the 90 rock-shafts P³, will elevate the blocks P².

R⁵ indicates a lever secured to one end of the shaft P⁶, on which the levers V³ are pivoted, whereby the track may be raised by hand. I have provided means for elevating 95 said tracks automatically upon each return movement of the cylinder, so that the impression-cloth will not engage the type, as follows: T indicates a vertical shaft rotatably mounted in suitable bearings in the machine-frame and 100 having an arm T² on its top end carrying a roller T³, adapted to be engaged by the segment K, and thus rock the shaft T. On the lower end of this shaft T is an arm V, and motion is imparted from this arm to one of 105 the arms P⁴ by means of the rod V², lever V³, and rod V⁴. These parts are so arranged that the segment K engages with the roller T only upon the return movement of the cylinder, and that when the arm T² is being held outwardly by said segment the track will be elevated at its central portion. To provide 110 means for adjusting the downward pressure of the impression-cylinder on the type, I have provided the springs x, placed in bores in the 115 frame, to engage the under surface of the blocks P² and the set-screws Y in the same bores to engage the lower ends of said springs.

Having thus described in turn the construction and operation of each feature of the invention, it is believed that their operation as a complete machine will be readily understood. Any common inking device may be used, and the papers are placed upon the feeding-platform, engaged by suitable devices on the impression-cylinder, and carried thereby over the type-bed, where the impression is made, and then discharged in the ordinary manner at the opposite end of the tracks.

I claim as my invention—

1. An improved printing press comprising a suitable frame, a type bed thereon, tracks at the side of the bed, an impression member mounted on said tracks, a yoke connected

- with the axle of the impression member, a series of lazy tongs levers pivotally connected with the said yoke at one end and with a stationary support at the other, the latter ends 5 having segmental gears on their meeting edges in mesh with each other, a vertical shaft mounted in the machine frame, an arm loosely mounted on said shaft to rotate in a horizontal plane, a link connected with said arm and 10 with one of the lazy tongs levers so that when the levers are at either limit of their movement the said arm and link will be in alignment and means for rotating said arm, for the purposes stated.
- 15 2. An improved printing press comprising a suitable frame, a type bed thereon, tracks at the side of the bed, an impression member mounted on said tracks, a yoke connected with the axle of the impression member a 20 series of lazy tongs levers pivotally connected with the said yoke at one end and with a stationary support at the other, the latter ends having segmental gears on their meeting edges in mesh with each other, a vertical shaft 25 mounted in the machine frame, an arm loosely mounted on said shaft to rotate in a horizontal plane, a link connected with said arm and with one of the lazy tongs levers, so that when the levers are at either limit of their movement 30 the said arm and link will be in alignment, a gear wheel loosely mounted on said shaft, spring actuated pawls connected with said gear wheel to engage said arm, and means for holding said pawls either in or out of engagement with the arm, for the purposes stated.
- 35 3. An improved printing press comprising a suitable frame, a type bed thereon, tracks at the side of the bed, an impression cylinder mounted on said tracks, cables wound upon 40 the ends of the impression cylinder and secured at the ends of the tracks, a yoke connected with the axle of the impression cylinder, a series of lazy tongs levers pivotally connected with the said yoke at one end and with 45 a stationary support at the other, the latter ends having segmental gears on their meeting edges in mesh with each other, a stub axle fixed in the machine frame in a vertical position, a gear wheel loosely mounted thereon, the 50 spring actuated pawls on said gear wheel as shown, a bar having the downward projection on its under side with an inclined face and cam surface as shown, to engage said pawls, an arm on said axle having a segmental downward projection, a link pivoted to the outer end of said arm and to the lazy tongs levers so that said link and arm will be in alignment when said levers are at the limits of their stroke, and means for operating said gear 55 wheel, for the purposes stated.
4. In an improved printing press the combination with a suitable frame, a type bed thereon, and tracks projecting above the sides of the type bed, of a block in the central portion of each track, a metal bar on each track secured thereto at its ends only, with its cen- 60 tral portion resting on said block, and means for elevating said blocks, for the purposes stated.
5. In an improved printing press, the combination with a suitable frame, a type bed thereon, and tracks projecting above the sides of the type bed, of a block in the central portion of each track, a metal bar on each track secured thereto at its ends only, with its central portion resting on said block, two rock shafts mounted in suitable bearings beneath the bed, one or more arms on each shaft projecting downwardly, rods pivotally connecting the arms, disks on the ends of said rock 70 shafts, blocks placed in notches in the disk and engaging the under edge of the aforesaid blocks, and means for imparting motion to one of said rock shafts, for the purposes stated.
- 75 6. In an improved printing press, the combination with a suitable frame, a type bed thereon, and tracks projecting above the sides of the type bed, of a block in the central portion of each track, a metal bar on each track secured thereto at its ends only, with its central portion resting on said block, and means for elevating said blocks, one or more coil springs placed in suitable vertical bores in the machine frame, with their upper ends impinging said blocks and set screws passed upwardly through said bores and in engagement with the lower ends of said springs, for the purposes stated.
- 80 7. An improved printing press, comprising a suitable frame, a type bed thereon, tracks at the side of the bed, an impression cylinder mounted on said tracks, a yoke connected with the axle of the impression cylinder, a series of lazy tongs levers pivotally connected with the said yoke at one end and with a stationary support at the other, the latter ends having segmental gears on their meeting edges in mesh with each other, a stub axle fixed in the machine frame in a vertical position, a gear wheel loosely mounted thereon, the 85 spring actuated pawls on said gear wheel as shown, a bar having the downward projection on its under side with an inclined face and cam surface as shown, to engage said pawls, an arm on said axle having a segmental downward projection and a segment projecting horizontally in an opposite direction from said arm, a link pivoted to the outer end of said arm and to the lazy tongs levers so that said link and arm will be in alignment when said levers are at the limits of their stroke, and means for operating said gear 90 wheel, flat metal bars on top of said tracks secured only at their ends, blocks under the central portions of said bars, two rock shafts mounted beneath the type bed, means for connecting them, devices fixed to their ends to engage and elevate said blocks when the shafts are rocked, a vertical shaft in the machine frame adjacent to said gear wheel, an arm on its top adapted to be engaged by said 95
- 100 105 110 115 120 125 130

horizontally projecting segment and means for connecting said shaft and the said rock shafts, for the purposes stated.

8. An improved printing press, comprising a suitable frame, a type bed thereon, tracks at the side of the bed, an impression cylinder mounted on said tracks, a yoke connected with the axle of the impression cylinder, a series of lazy tongs levers pivotally connected to the said yoke at one end and with a stationary support at the other, the latter ends having segmental gears on their meeting edges in mesh with each other, a stub axle fixed in the machine frame in a vertical position, a gear wheel loosely mounted thereon, the spring actuated pawls on said gear wheel as shown, a bar having the downward projection on its under side with an inclined face and cam surface as shown, to engage said pawls, an arm on said axle having a segmental downward projection and a segment projecting horizontally in an opposite direction from said arm, a link pivoted to the outer end of said arm and to the lazy tongs levers so that

said link and arm will be in alignment when 25 said levers are at the limits of their stroke, and means for operating said gear wheel, flat metal bars on top of said tracks secured only at their ends, blocks under the central portions of said bars, two rock shafts mounted 30 beneath the type bed, means for connecting them, devices fixed to their ends to engage and elevate said blocks when the shafts are rocked, coil springs placed in suitable vertical bores in the tracks to impinge the under 35 sides of said blocks, and set screws in said bores with their ends in engagement with the lower ends of said springs, a vertical shaft in the machine frame adjacent to said gear wheel an arm on its top adapted to be engaged by said horizontally projecting segment and means for connecting said shaft and the said rock shafts, for the purposes stated.

HARVEY L. FISHER.
